CLAIM

I claim the ornamental design for a simulated, miniature lacrosse stick head for use with a writing utensil, or an object of similar dimensions, as shown and described

DESCRIPTION

FIG. 1 is a perspective view of a simulated, miniature lacrosse stick head for use with a writing utensil, or an object of similar dimensions in accordance with the present invention;

FIG. 2 is a view of the top end thereof;

FIG. 3 is a view of the bottom end thereof;

FIG. 4 is a view of the front side thereof;

FIG. 5 is view of the back side thereof;

FIG. 6 is a view of the right side thereof; and,

FIG. 7 is a view of the left side thereof.

The broken lines in FIGS. 1 and 3 define the bounds of the claimed design and form no part thereof.
